FRED H. YEOMANS, OF DETROIT, MICHIGAN

SPACING STRIP FOR BOTTLE-SHIPPING CRATES

Application filed November 15, 1928. Serial No. 319,494.

This invention relates to an improved form of metallic spacing or separating strip used particularly in the shipping and handling of milk bottles and similar articles in quantity, and has for its object an improved contouring of such a part which not only tends to greater rigidity of the individual strips, but as well makes for greater cleanliness and impossibility of concealment of masses of milk or other fluid which have accidentally been spilled upon these parts and which conditions of cleanliness forbid leaving unwashed.

In the drawings:

Figure 1 is a perspective of an intersecting pair of my improved spacing strips showing the separation and resultant aeration of the parts.

Figure 2 is a plan view of a corner of a shipping box equipped with my improved form of spacing, and with an indication of the bottles in position thereto.

Figure 3 is a sectional elevational view of a pair of intersecting strips.

A indicates a shipping box or crate with a pair of strips as B and C extending across the top thereof and intersected by a strip D running at right angles thereto, the ends of each strip being secured to the top edge of the box in any manner desired. Each strip is centrally grooved or ribbed, as at E, throughout its length, and in addition there are provided at intervals lateral inbendings or pressed-in portions F, the effect of which is to finally position those portions of the bordering webs L of the metal strip which lie on either side of the central rib in planes almost perpendicular to that of the strip as a whole, the now lower edges of these inbent portions, which constitute the lateral edges of the strip, extending appreciably beneath the plane of the strip as a whole. The provision of these alternated inbent portions F coincides in position and in distance from one another with the intended positions of the milk bottles G as arranged within the shipping box, and between each of these doubly inbent portions just described the plain though centrally ribbed portions of the metal strip remain unchanged. These inbent portions, such as J and K in Figure 1, which form the alternated integral parts

of the lengthwise and crosswise strips of a box, intersect one another, thus forming squared sections with intermediate slightly inbent sides formed by the pressed-in portions F, for the reception of the individual milk bottles.

Of course, if it were desirable, these intersecting portions, as J and K, could be riveted or otherwise secured together, forming a sort of lattice work, but just the opposite of this has been found to be the most desirable construction, namely a permanent definite spacing of the two metal strips, except for the contact between them along the very narrow lines formed by the ribs E, so that if milk or other fluid is spilled thereover it cannot work its way into the very thin space between the intersecting strips and there gradually dry and become sour. It is my belief that these parts should be thus definitely and appreciably spaced from one another, so that except for the quite narrow lines of contact where the underface of the unbent portion of one of the metal strips, as J, engages the top edge of the rib E which traverses the section K, there will be no actual contact between them. The provision and maintained permanence of the space thus provided make it easy for the access of a cleansing stream of steam or similar cleansing medium between the adjacent but spaced surfaces of the strips J and K, for the removal of any fluid remaining thereon whose continued presence there would be objectionable; at the same time the reinforcing effect upon the relatively thin metal strip as such, due to the presence not only of the lengthwise rib E, but as well the alternated inbent portions F, produces a surprisingly rigid spacing member which is both adequate as regards its strength to keep the bottles apart, and as well is so light as to add very little weight to the completed shipping crate or box.

What I claim is:

1. As a new article of manufacture, a sheet metal strip provided with a continuous longitudinal rib midway between its lateral edges and having its plane edge portions inbent at spaced intervals to form bottle-engaging surfaces, the rib on each strip being adapted to

engage the plane portions of a similar strip arranged at right angles thereto to the exclusion of the contact therewith of the flanking plane portions of its own strip.

5 2. Means for spacing and holding against undesired lateral displacement a plurality of articles positioned within a shipping box, comprising a plurality of coordinated strips arranged intersectingly of one another adjacent the top of the box, each strip being ribbed throughout its lengthwise extent and having spaced portions of its plain lateral webs downwardly inbent, each intermediate portion of each strip being paired with a corresponding portion of a strip extending transversely of the first mentioned strip and having its lateral webs held in spaced relation therefrom by the engagement of the lengthwise rib on one or the other of the strips 10 against the plain web portions of the other strip.

3. As a new article of manufacture, a sheet metal strip adapted for cooperative intersecting association with similar strips, each 25 strip having a continuous longitudinal rib and being provided as well with spaced additionally inbent portions adapted for holding engagement about the sides of bottles positioned in the rectangular spaces bounded 30 by the several intersecting strips, the rib in those portions of each strip which intersect or overlap corresponding portions of the other strips affording a space for the access of a cleansing medium to all parts of the surfaces 35 this over-engaging one another.

In testimony whereof I sign this specification.

FRED H. YEOMANS.
